UNITED STATES PATENT OFFICE.

VICTOR R. JOHNSON, OF SOMERVILLE, MASSACHUSETTS.

FOLDING CRADLE.

1,209,447.

Specification of Letters Patent. Patented Dec. 19, 1916.

Application filed September 29, 1914. Serial No. 864,145.

To all whom it may concern:

Be it known that I, VICTOR R. JOHNSON, a subject of the King of Sweden, residing at Somerville, in the county of Middlesex and State of Massachusetts, have invented 5 certain new and useful Improvements in Folding Cradles; and I do hereby declare the following to be a full, clear, and exact description of the invention, such as will 10 enable others skilled in the art to which it appertains to make and use the same.

This invention relates to a folding cradle for use by automobilists for protecting them from lying flat upon the ground when 15 crawling beneath a machine for repairing the same.

The primary object of the invention is the provision of a cradle which is made of a plurality of hingedly connected sections, 20 whereby the cradle may be folded up to form a composite article which may be conveniently carried about within the tool box of an automobile, and also to mount casters upon the under surface of the cradle where- 25 by when a person is lying upon the same beneath the automobile they may move about from place to place.

With the foregoing and other objects in view this invention consists in such novel 30 features of construction, combination and arrangement of parts as will be hereinafter more fully described, illustrated in the accompanying drawings and claimed.

In describing the invention in detail reference will be had to the accompanying 35 drawings wherein like characters designate like or corresponding parts throughout the several views, and in which:—

Figure 1 is a plan view of the improved 40 cradle showing the same in an extended position. Fig. 2 is an end view of the cradle showing it folded. Fig. 3 is a cross sectional view through the folded cradle. Fig. 4 is a side elevation of the cradle in an ex- 45 tended position, and Fig. 5 is a side view of the cradle in a folded position showing part thereof broken away.

Referring more particularly to the drawings, 1 designates the cross slats of the 50 cradle which have the terminal ends secured to the under surface of the horizontal portion of various strips 2, 3, 4, 5, 6, 7, 8, and 9 of angle iron. The strips of angle iron are connected in alinement with each other for 55 forming two sides 10 and 11 of the cradle, as is clearly shown in Fig. 1 of the draw-

ings and the strips 4, 5, 8, and 9 have their vertical sides extending beyond the end of the horizontal side for forming ears 12. The ears 12 are pivotally connected to the 60 vertical sides of the angle iron next to the one upon which they are formed, as is clearly shown in the drawing. Each alternate strip of angle iron which forms the sides 10 and 11 is of reduced size with respect to the strip next thereto, so that they may be folded in the position shown in Figs. 2 and 3 of the drawings for forming a compact article. The alternate strips which are shorter than the strips next there- 65 to increase in length to facilitate the proper folding of the cradle.

Certain of the slats 1 have casters 16 secured thereto, which casters are provided for resting upon the ground when the cradle 75 is in an extended position for facilitating the moving about of the cradle by a person who is lying or sitting thereupon, and certain of said slats 1 have longitudinal slots 80 18 formed adjacent the sides to receive the casters 16 when the cradle is folded.

The strips 2 and 6 of angle iron are hingedly connected to the strips 3 and 7 respectively by hinges 17, which permit of the compact folding of these strips for positioning them centrally of or interiorly of the other strips when the cradle is in a folded position.

When it is desired to use the cradle beneath an automobile or like vehicle, the 90 same is unfolded to assume an extended position as is shown in Figs. 1 and 4 of the drawings and the person who is going to repair the machine lies upon the cradle, and propels himself beneath the vehicle in the 95 desired position for working upon the mechanism of the same. The cradle prevents the person from lying flat upon the ground and soiling his clothes upon contact with the dust or dirt of the roadway.

In reducing the invention to practice certain minor features of construction, combination and arrangement of parts may necessitate alterations to which the patentee 100 is entitled provided such alterations are comprehended within the scope of what is claimed.

What is claimed is:—

In a cradle, for use by autoists, a plurality of relatively large and small sections 110 hingedly connected adapted to form when folded a substantially rectangular object,

the relatively large sections forming the top and bottom and the small sections forming the sides, and casters secured on the under side of said sections, said sections having recesses formed in their upper surface to receive said casters when the sections are folded for the purpose specified.

In testimony whereof I affix my signature in presence of two witnesses.

VICTOR R. JOHNSON.
